UNITED STATES PATENT OFFICE.

JOHN L. JUDSON AND WILLIAM A. COGSWELL, OF ROCHESTER, NEW YORK,
ASSIGNORS TO JUNIUS JUDSON & SON, OF SAME PLACE.

GOVERNOR.

SPECIFICATION forming part of Letters Patent No. 254,775, dated March 7, 1882.

Application filed May 31, 1881. (No model.)

To all whom it may concern:

Be it known that we, JOHN L. JUDSON and WILLIAM A. COGSWELL, both of Rochester, Monroe county, New York, have invented a certain new and useful Improvement in Governors; and we do hereby declare that the following is a full, clear, and exact description of the same, reference being had to the accompanying drawings, in which—

10 Figure 1 is an elevation, partially in section, of a governor showing our improvement. Fig. 2 is a plan of the same, one of the balls being in section to show the cross-bar and its attachments.

15 Our improvement relates to what is known as the "Judson" governor; and it consists of an arrangement of springs and adjustable cross-bars connecting the balls, constructed, arranged, and operating as hereinaftermore fully described.

The governor is of ordinary and well-known construction, and does not require special description.

20 A A are the balls, which are flattened on the sides, instead of being spherical, as is ordinarily the case. In these balls are made horizontal slots or passages a a, extending through the balls, and being of considerable width, as shown. In these slots rest cross-bars B B, 25 through which pass screws C C, turning loosely in the ball. The cross-bars form nuts, and as the screws are turned said cross-bars will be moved out or in, as the case may be. The ends of the cross-bars project some distance 30 beyond the sides of the balls, and have hooks b b formed thereon, as shown in Fig. 2.

35 D D are coiled springs, made of light spring-wire, and having loops c c, which rest on the hooks b b, and the springs thus form a connection between the cross-bars on opposite sides of the balls.

40 It is found that cross-bars passing through slots in the balls, projecting on opposite sides and made adjustable forward and back, are 45 convenient attachments for the springs, as the

latter can be attached and removed with the greatest facility, and the tension can be adjusted with great accuracy on both springs at once, so that the governor can be adapted to the work for which it is intended without difficulty.

If desired, one only of the balls may be provided with the slot and adjusting-screw, the cross-bar being made fixed and stationary in the opposite ball.

50 By the use of two coiled springs on opposite sides of the balls connected directly from one ball to the other, and adjustable to different tensions, the action is balanced, and the balls, while speeding the governor, (or requiring an increased speed before commencing to rise,) are 55 at the same time much more sensitive to variations than the ordinary weighted balls, or those balls which are attached to elliptic or other flat springs whose tension increases by 60 centrifugal action.

65 By the use of springs extending directly from ball to ball the tendency is to reduce the friction on the pivots of the arms, as the springs draw against the centrifugal action and draw 70 up toward the pivots, instead of throwing out against the pivots, as where weighted balls are used.

75 We disclaim springs connecting the balls and attached to bearings on top of the balls.

What we claim as new is—

In a governor, the combination, with the balls A A, of cross-bars B B, attached to the balls and made adjustable forward and back, and coiled springs D D, connecting the cross-bars, as shown and described, and for the purpose specified.

In witness whereof we have hereunto signed our names in the presence of two subscribing witnesses.

JNO. L. JUDSON.
W. A. COGSWELL.
